UNITED STATES PATENT OFFICE.

THOMAS LINDSEY, OF LINCOLN, ILLINOIS, ASSIGNOR TO HIMSELF AND
J. H. BEIDLER.

IMPROVEMENT IN SEEDING-MACHINES.

Specification forming part of Letters Patent No. 27,865, dated April 10, 1860.

To all whom it may concern:

Be it known that I, THOMAS LINDSEY, of Lincoln, in the county of Logan and State of Illinois, have invented a new and Improved Seeding-Machine; and I do hereby declare that the following is a full, clear, and exact description of the same, reference being had to the annexed drawings, making a part of this specification, in which—

Figure 1 is a transverse vertical section of my invention, taken in the line xx , Fig. 2; Fig. 2, a back elevation of the same, partly bisected, as indicated by the line yy , Fig. 1; Fig. 3, a detached plan view of a portion of the seed-distributing device.

Similar letters of reference indicate corresponding parts in the several figures.

To enable those skilled in the art to fully understand and construct my invention, I will proceed to describe it.

A represents an axle with a wheel, B, at each end; and aa are cross-bars, which are attached, one at each end of the axle A.

To the ends of the cross-bars aa bars bb are secured, the latter being parallel with the axle A.

To each cross-bar aa a standard, c , is attached, and these standards support a seed-box, B, which is nearly equal in length to the axle A, as shown clearly in Fig. 2.

Immediately underneath the seed-box B a shaft, d , is placed longitudinally, said axle having a driving-pulley, e , at one end around which a belt, f , passes from a pulley, g , at the inner end of the hub of one of the wheels B, as shown in Fig. 2.

On the axle d a series of wheels, h , are placed. These wheels pass up or work through slots in the bottom i of the seed-box, each wheel being inclosed below the seed-box by a case, j , as shown clearly in Fig. 1. The wheels h have their peripheries notched or recessed to form seed-cells k , and the partitions l , which form the cells, are shaped like ratchet-teeth, as shown clearly in Fig. 1. This form of the partitions causes the seed-cells to have one side much more inclined than the other. The object of this will be presently stated.

Within the seed-box B there is placed longitudinally a slide, C. This slide is formed of a plate having oblong slots, m , made in it, through

which guide-screws n pass. (See Fig. 3.) This slide C is placed on the bottom i of the hopper and directly in front of the wheels h , and the back edge of the slide C directly in front of each wheel, is notched, as shown at o , one or more notches being made in front of each wheel. If more than one notch is employed in front of each wheel, said notches are made of different depths, as shown in Fig. 3. The slide C may be soadjusted as to bring either of the notches o in front of the wheels h , or neither of them. When the notches are shoved entirely at one side of the wheels the back edge of the slide is brought nearly in contact with the wheels, the latter being allowed to work just clear of the slide, in order to prevent friction.

To the lower end of the cases j flexible tubes p are attached, one to each. These tubes are connected at their lower ends to the upper ends of vertical tubes q , which are of metal and secured at their upper ends in the bars bb , the tubes of one bar being in line with the centers of the spaces between the others. The flexible tubes p are attached alternately to the tubes q , and to the lower end of each tube q a share, D, is attached. These shares D are of double-mold-board form, and they have inclined back edges, as shown in Fig. 1, to admit of the earth passing behind and falling into and filling the furrows, and consequently covering the seed dropped therein. The front edges of the tubes q are made sharp, as shown at r , forming colters.

To the back part of the axle A a curved support, E, is attached for the driver's seat F, and to the front part of said axle the draft-pole G is attached.

The operation is as follows: The seed-box B is supplied with a requisite quantity of seed, and as the machine is drawn along the wheels h are rotated from one of the wheels B by the band f in the direction indicated by the arrow. The seed-cells k of course fill with seed, and the cells, as the wheels h rotate, convey the seed out from the hopper and discharge it into the tubes p , through which the seed passes into the tubes q , and is discharged into the furrows formed by the shares D. The seed-cells k , in consequence of having one quite oblique side, are allowed to carry their seed, without crushing or breaking it, past the edge of the slide

C, as will be fully understood by referring to Fig. 1. Were the partitions *l* arranged radially, their outer edges would serve to split and bruise the seed while passing the inner edge of slide C; but the obliquity of the partitions prevents this contingency, as the outer edge of each partition does not pass the inner edge of slide C until the seed in the cell below it has passed below the upper edge of the slide. This is quite an important feature of the invention.

In order to vary the quantity of seed to be planted in a given area, the slide C is adjusted to sow the smallest quantity over a given space. The slide C is moved so that the notches *o* will not be in front of the wheels *h*, and the inner edge of slide C brought nearly in contact with wheels *h*. This quantity is increased by moving the slide to the shallowest notches *o* in front of the wheels. The quantity is still further increased by moving the slide to bring

the next deepest notch *o* in front of the wheels *h*, and so on, the deeper the notches *o* the wider the space between the wheels *h* and slide C, and consequently the more profuse the distribution of the seed.

The shares D, as before stated, form the furrows and permit the same to fill behind the shares. The shares D are placed at such a distance apart as to fully plow the ground or act upon its whole surface between them.

Having thus described my invention, I claim as new and desire to secure by Letters Patent—

The arrangement of the notched slide C, wheels *h*, oblique partitions *l*, seed-cells *k*, tubes *q p*, and shares D, as and for the purpose herein shown and described.

THOMAS LINDSEY.
